Frank C. Jones

BY
Albert D. Dietrich
ATTORNEY

UNITED STATES PATENT OFFICE

FRANK C. JONES, OF PARMA, OHIO

CIGARETTE HOLDER

Application filed September 28, 1931. Serial No. 565,627.

The invention is a new and improved cigarette holder, especially designed for ladies' use.

It has for an object to provide a simple, neat and inexpensive holder whereby the smoker may get the full cigarette flavor and also avoid the odor and stain on the fingers which frequently occurs to those who smoke cigarettes without a suitable holder.

10 Further, it is an object to provide a holder having a split clamp and means to adjust the clamp to hold or release the cigarette in a convenient, easy and satisfactory manner.

15 Further, the invention has for an object to provide a holder of such construction that the cigarette is not smoked through the holder, thus eliminating strong pipe flavor and accumulation of saliva which frequently takes place with the use of the old type holder, and my invention further eliminates the necessity of touching the cigarette after it has once been placed in the holder.

20 Other objects will in part be obvious and in part be pointed out hereinafter.

25 To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawing, in which:—

30 Figure 1 is a perspective view showing the invention in use.

Figure 2 is a vertical longitudinal section of the same with the clamp closed.

35 Figure 3 is a similar view to Figure 2 but with the clamp open.

40 Figure 4 is a side elevation of the upper section of the body of the holder.

Figure 5 is a side elevation of the lower section of the body of the holder.

45 Figure 6 is an end view of the lower section.

Figure 7 is a side elevation of the elevator bushing.

50 Figure 8 is an end elevation of the same.

Figure 9 is a plan of the same.

Figure 10 is a side elevation of the elevator operating shaft.

Figure 11 is a perspective view of the split bushing.

Figure 12 is an enlarged cross section on 55 the line 12—12 of Figure 2.

In the drawing, in which like numerals of reference indicate like parts in all of the figures, 1 represents the upper section of the tubular body of the holder, which section 60 has a frusto-conical end 2 serving as one element of a clutch. The lower section of the body of the holder 3 has a reduced end 4 to fit into the upper section 1 and this reduced end 4 at diametrically opposite sides is provided with concaved portions 5 of suitable radius, the purpose of which will presently appear.

Fitted into the lower end of the body section 3 is a split bushing 6 split diagonally as 70 at 7, and having a bearing aperture 8 to fit the reduced portion 10 of the elevator operating shaft as a bearing therefor. By reason of the reduced portion 10, the bushing 6 75 serves to prevent longitudinal movement of the elevator shaft 9 while permitting rotation of the shaft by means of the finger piece 11 formed on the outer end thereof. 12 is a pin hole in the inner end of the shaft 9 80 for the reception of the elevator pin 13 which also passes through diagonal or spiral slots 14 in the elevator bushing 15.

The elevator bushing 15 fits within the reduced portion 5 of the lower body half and it, too, has concaved sides 16 registering with the sides 5 but of a lesser radius so as to provide spaces between the concaved surfaces 5 and 16 into which the arms 19 of the split clamp member project, the arms 19 90 having fingers 18 at their inner ends to fit into recesses or apertures 17 in the concaved portions 16 of the elevator bushing 15 when the parts are assembled.

The split clamp consists of the two arms 95 19 having the fingers 18 and also having cigarette gripping portions 20 of segmental circular form, the arms 19 being of a springy nature and projecting through the opening in the reduced end of the frusto-conical part 100

2 of the upper body member 1 and serving as the other element of the clutch.

When the parts are assembled as shown in Figures 2 and 3, it will be seen that the shaft 9 may be rotated in one direction or the other 5 through a part of a revolution and when so rotated its motion is translated by the pin and slot connection 13—14 into a longitudinal or reciprocatory motion in the elevator bushing 15 which consequently advances or 10 retracts the split clamp with respect to the opening in the end of the frusto-conical part 2 and thereby closes and opens the clamp elements 20 proper to grip or release the cigarette. Figure 2 shows the gripping position and Figure 3 shows the open or released position.

It should be understood that the split bushing 6 may be held by retaining friction 20 and the two parts 1 and 3 of the body are held together also by retaining friction, thus making it possible to take the holder apart for repairs or replacements when necessary and yet holding the parts together with sufficient tenacity to prevent their accidental displacement.

While I have shown a preferred embodiment of the invention in the accompanying drawing and have described the same herein, 30 I desire it understood that changes in the details of construction, combination and arrangement of parts within the scope of the appended claims may be made without departing from the spirit of the invention.

35 What I claim is:

1. A cigarette holder comprising a tubular body having an end with an opening of reduced diameter, a pair of clamp arms projecting through said end and into said body, 40 an elevator bushing slidably held within said body, means anchoring said arms to said bushing, means holding said bushing against turning in the body, an elevator operating shaft rotatably located in said bushing, and a pin and inclined slot connection between said shaft and bushing; means holding said shaft against slidable movement in the body and means on said shaft by which it may be turned in the body.

50 2. A cigarette holder comprising a tubular body having a tapered end, a split clamp held in said end and having a cigarette receiving portion located outside the body, a member within said body mounted for movement along the axis of the body only, means for anchoring said clamp to said member, means carried by the body and including a rotatable member and a movement transmitting and translating device within the body for 55 moving said member along the axis of the body to open and close the clamp.

60 3. A cigarette holder comprising a two-part tubular body, the parts of which are held together end to end by retaining friction, one end of said body being tapered, a

split clamp within said body and projecting through said tapered end in cooperation therewith, said body having internal longitudinal guides, a bushing located in said body in association with said guides to permit movement longitudinally of the body while holding the bushing against turning, means connecting said clamp and bushing to move together, and means mounted in said body and operable from the outside of the same for moving said bushing back and forth to close or open the clamp accordingly.

4. A cigarette holder comprising a two-part tubular body, the parts of which are held together end to end by retaining friction, one end of said body being tapered, a split clamp within said body and projecting through said tapered end in cooperation therewith, said body having internal longitudinal guides, a bushing located in said body in association with said guides to permit movement longitudinally of the body while holding the bushing against turning, means connecting said clamp and bushing to move together, a second bushing also mounted in said body adjacent the end thereof opposite the tapered end and having a bearing portion, a shaft rotatable in said body with bearing in said bearing portion and held against longitudinal movement by said bearing portion, means connecting said shaft with said first mentioned bushing and having provisions for translating the rotary motion of the shaft into longitudinal motion in the bushing.

5. A cigarette holder comprising a two-part tubular body, the parts of which are held together end to end by retaining friction, one end of said body being tapered, a split clamp within said body and projecting through said tapered end in cooperation therewith, said body having internal longitudinal guides, a bushing located in said body in association with said guides to permit movement longitudinally of the body while holding the bushing against turning, means connecting said clamp and bushing to move together, a split bushing also mounted in said body, a shaft rotatably held within said body by said split bushing and against longitudinal movement therein, said first named bushing having a spiral slot, and a pin passed through said shaft into said slot for the purpose described.

FRANK C. JONES.
